T. NOWLAND

SAFETY HOOK

Filed June 16, 1924

INVENTOR.
Theopolis Nowland

BY
Geo. P. Kimmel.
ATTORNEY.

UNITED STATES PATENT OFFICE.

THEOPOLIS NOWLAND, OF NEWPORT, RHODE ISLAND.

SAFETY HOOK.

Application filed June 16, 1924. Serial No. 720,314.

To all whom it may concern:

Be it known that I, THEOPOLIS NOWLAND, a citizen of the United States, residing at Newport, in the county of Newport and State of Rhode Island, have invented certain new and useful Improvements in Safety Hooks, of which the following is a specification.

This invention relates to safety hooks for loading and unloading purposes and of that type that may be termed a "cargo" hook, and has for its object to provide, in a manner as hereinafter set forth, a safety hook provided with a retaining element for the load and locking means for said element actuated manually and exteriorly thereof to release the same to permit of the removal of the load.

A further object of the invention is to provide a safety hook, in a manner as hereinafter set forth, with a retaining element for the load arranged to overlap exteriorly the bill of the hook and a spring controlled locking means cooperating exteriorly and interiorly with respect to the locking element for maintaining the same in locking position, and with said means manually operated exteriorly of the hook body for the purpose of releasing the locking element to permit of the removal of the load.

Further objects of the invention are to provide, in a manner as hereinafter set forth, a safety hook, which is comparatively simple in its construction and arrangement, strong, compact, thoroughly efficient and convenient in its use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a side elevation of a safety hook, in accordance with this invention, illustrating the retaining element in retain-

ing position in full lines and released position in dotted lines. 55

Figure 2 is a vertical sectional view of the hook when closed.

Figure 3 is an edge view, partly in section, of the hook.

Figure 4 is a perspective view of the locking member. 60

Figure 5 is a perspective view of the shifting member for the retaining element.

Referring to the drawings in detail, 1 indicates the shank of the hook, which is of 65 tapered contour and provided near its outer end with an opening 2, which is eccentrically disposed with respect to the longitudinal center of the shank.

Extended from the inner end of the shank 70 1, at one side thereof, is a curved hook 3, formed with a bill 4, spaced from the other side of the inner end of the shank 1.

The inner end of the shank 1 is provided with a groove 5, which is continued, as at 75 6, on the inner face of the hook 3 for a portion of the length of said inner face. The outer end of the groove 5 is open, and the inner end closed by a wall 7, arranged in the hook 3. The outer face of the bill 4 80 is provided with a rectangular socket 8, a substantial distance from the free terminus of the bill.

The hook 3 has its outer edge flush with one side edge of the shank 1, and the other side edge of the shank 1 is formed with a groove 85 9, having an upper end wall 10 and an upwardly extending and inwardly inclined bottom 11. The groove 9 extends from a point in close proximity to the outer end of the groove 5 and gradually increases in depth towards the end wall 10 thereof. The end wall 10 of the groove 9 provides an abutment for a locking member to be presently referred to. 90

The retaining element is referred to generally by the reference character 12 and consists of a curved body portion 13 of a length to overlap the outer edge of the bill 4, and said body portion 13 has its inner 105 face provided with a lug 14 for seating in the socket 8 when the hook is closed. The forward part of the body portion 13 has its outer edge provided with a groove 15, which terminates in an opening 16 at the forward 105 terminus of the body portion 13.

The forward terminus of the body portion 13 is provided with a pair of spaced arms 17, 18, which are offset with respect to said forward terminus and each of said arms is positioned against the shank 1, which is formed with an opening 19, in alignment with the opening 2 and positioned in proximity to the groove 5. Each of said arms is apertured, as at 20, and extending through the apertures of the arms and the opening 19 is a bolt 21 for pivotally connecting the retaining element 12 to the shank 1. The bottom 22 of the groove 15 inclines inwardly towards the opening 16 to provide a clearance for the pivoted end of a locking member to be presently referred to. The bolt 21 has its head 23 abut against the arm 18 and its shank extended from the arm 17, and mounted on the shank is a securing nut 24.

The locking member for the retaining element is indicated generally by the reference character 25 and is carried by said retaining element 12 and operates in the groove 9 and engages the wall 10 of the latter for the purpose of maintaining the retaining element 12 in retaining position to close the hook. The locking member 25 comprises a forward portion 26, an intermediate portion 27 and a rear portion 28. The intermediate portion 27 is of greater width than the portions 26 and 28. The inner terminus of the rear portion 28 is enlarged, as indicated at 29, and provided with an opening 30 and positioned in the groove 15 and opening 16 of the retaining element 12. The forward terminus of the body portion 13 of the retaining element 12, as well as the rear termini of the arms 17 and 18 are apertured, as indicated at 31 and which align with the opening 30 of the locking member and extending through said aligning apertures and openings is a headed bolt 32, which has the shank thereof extended from the arm 17, and mounted on said shank is a securing nut 33. The bolt 32 pivotally connects the locking member 25 to the retaining element 12.

The intermediate portion 27, as well as the forward portion 26, of the locking member, projects outwardly from the arms 17 and 18 and said forward portion 26 is adapted to slide in the groove 9 and when the member 25 is in locking position, the forward terminus of the forward portion 26 abuts against the wall 10 of the groove 9 which holds the retaining member against the bill 4 and with the lug 14 in the socket 8, whereby the hook 3 is closed.

The locking member 25 has its outer face provided with a lengthwise groove 34, in which slides a flat spring 35 for controlling said locking member 25. The spring 35 is of a length to extend into the groove 15 and is fixedly connected to the retaining element 12 by the hold-fast device 36. A pin 37 ex-

tends transversely of the groove 15, forwardly of the hold-fast device 36 and bears on the spring 35 and constitutes a holding-down element for the rear portion of the spring in advance of the hold-fast device. 70

The locking member 25 is shifted to released position manually. The released position of the locking member 25 is indicated in dotted lines in Figure 1 and when shifted to released position it is moved outwardly 75 against the action of the spring 35 and the forward end of said member 25 slides on the shank 1, forwardly with respect to the wall 10 of the groove 9.

The locking member 25, due to the action of the spring 35, automatically assumes locking position when the retaining element is manually shifted to retaining position with the lug 14 seated in the socket 8.

When the locking member 25 is manually shifted to released position, the retaining element 12 is automatically shifted to open position and for such purpose a shifting member 38 is employed and which is in the form of a spring controlled pawl. The shifting member 38 has one side edge thereof curved, as indicated at 39, to ride against the inner side edge of the retaining element 12. The other side edge of the member 38 is flat, as at 40, and riding against said edge 40 is a curved controlling spring 41 which has a portion thereof project from the groove 5. The spring 41 is extended around a pin 42, which extends transversely of that portion 6 of the groove 5, formed in the inner side edge of the hook 3. The spring 41 has one end fixedly secured in the portion 6 of the groove 5, by a hold-fast device 43, which is arranged rearwardly of and spaced from the pin 42. 105

The member 38 has one end formed with an opening 44, and the apertured end of the member 38 is positioned in the groove 5. Extending through the shank 1 and the aperture 44 of the member 38, is a bolt 46 110 for pivotally connecting the member 38 to the shank 1. The member 38 projects towards and engages at all times the inner face of the retaining element 12, and through the action of the spring 41 when the locking member 25 is shifted to released position, the member 38 forces the retaining element 12 to open position, as indicated in dotted lines, Figure 1. 115

As before stated, the spring 41 slides 120 against the edge 40 of the member 38 and is retained thereon through the medium of a pair of spaced guide lugs 47, 48, which are integral with the sides of the member 38 and project from the edge 40. 125

The spring 41 not only acts as a means to provide for the shifting of the retaining element 12 to open position, but when the element 12 is in closed position, the spring 41 further acts to retain the member 25 in 130

abutting engagement with the wall 10, as such spring 41 will exert an outward pressure on the element 12 which will be transmitted to the member 25.

5 Extending through the opening 2 of the shank 1, is a pivot element 49 for a shackle 50.

The construction of safety hook as referred to, is such that the hook 3 cannot be 10 opened until the locking member 25 is shifted manually outwardly on its pivot and upon the shifting of the locking member 25 outwardly, the retaining element 12 will be automatically shifted to open position and 15 by this arrangement the hook 3 is always maintained closed until the locking member 25 is manually released. As before stated, when the retaining element 12 is manually shifted to close the hook 3, the member 25 20 automatically assumes locking position to lock the element 12 in closed position, and it is thought that the many advantages of such construction of safety hook can be readily understood, and although the preferred embodiment of the invention is as 25 illustrated and described, yet changes in the details of construction can be had which will fall within the scope of the invention as claimed.

30 What I claim is:—

1. A safety hook comprising a shank having a hook element extended therefrom, a retaining element pivotally connected to the shank and overlapping and engaging in the 35 outer edge of the hook element to close the same, a spring controlled locking member pivotally connected at one end to and projecting from the outer edge of said retaining element, said locking member engaging in one side edge of said shank for locking the retaining element in closed position, and a spring controlled shifting member pivotally connected to the shank and bearing against said retaining element for automatically 40 shifting it to open position when the locking member is released and further exerting a holding pressure on the locking member when the latter engages in the shank.

55 2. A safety hook comprising a shank having a hook element extended therefrom, a retaining element pivotally connected to the shank and overlapping and engaging in the outer edge of the hook element to close the same, a spring controlled locking member pivotally connected at one end to and projecting from the outer edge of said retaining element, said locking member engaging in one side edge of said shank for locking the 60 retaining element in closed position, and a spring controlled shifting member pivotally connected to the shank and bearing against said retaining element for automatically shifting it to open position when the locking member is released and further exerting a 65 holding pressure on the locking member when the latter engages in the shank.

holding pressure on the locking member when the latter engages in the shank, said hook having its outer edge provided with a socket and said retaining element formed with a lug seating in the socket when the 70 retaining element closes the hook.

3. A safety hook comprising a shank having a hook element extended therefrom, said hook having its bottom edge and a side edge 75 grooved, a retaining element pivotally connected to the shank and overlapping the hook element to close the same, a spring controlled locking member having one end pivotally connected in said retaining element and its other end seating in the groove in the side edge of the shank for locking the retaining element in closed position, and a spring controlled shifting member having one end pivotally connected in the groove at the inner edge of the shank and bearing against said retaining element for automatically shifting it to open position when the locking member is released and further exerting a holding pressure on the locking member when the latter is in locking position. 80

4. A safety hook comprising a shank having a hook element extended therefrom, said hook having its bottom edge and a side edge 85 grooved, a retaining element pivotally connected to the shank and overlapping the hook element to close the same, a spring controlled locking member having one end pivotally connected in said retaining element and its other end seating in the groove in the side edge of the shank for locking the retaining element in closed position, a spring controlled shifting member having one end pivotally connected in the groove at the inner edge of the shank and bearing against 90 said retaining element for automatically shifting it to open position when the locking member is released and further exerting a holding pressure on the locking member when the latter is in locking position. 95

5. A safety hook comprising a shank having a hook element extended therefrom, a retaining element pivotally connected to the shank and overlapping the hook element to close the same, a locking member pivotally carried by said retaining element and engaging in the shank for locking the retaining element in closed position, means carried by the retaining element and engaging the locking member for maintaining it in locking position, and spring controlled pivoted means carried by the shank and engaging said retaining element for automatically shifting it to open position when the locking member is released and further exerting 100 105 110 115 120 125 130

4
a holding pressure on the locking member when the latter is in locking position.

6. A safety hook comprising a shank having a hook element extended therefrom, a retaining element pivotally connected to the shank and overlapping the hook element to close the same, a locking member pivotally carried by said retaining element and engaging in the shank for locking the retaining element in closed position, means carried by the retaining element and engaging the locking member for maintaining it in locking position, spring controlled pivoted means carried by the shank and engaging said retaining element for automatically shifting it to open position when the locking member is released and further exerting a holding pressure on the locking member when the latter is in locking position, said hook element having its outer edge provided with a socket, and said retaining element having its inner edge formed with a lug seating in said socket when the retaining element is in closed position.

7. A safety hook comprising a shank having a hook element extended therefrom, a retaining element pivotally connected to the shank and overlapping the hook element to close the same, a grooved locking member pivotally carried by said retaining element and engaging in one side edge of the shank for locking the retaining element in closed position, a controlling spring carried by the retaining element and sliding in the groove of the locking member for maintaining it in locking position, a grooved shifting member pivotally carried by the shank, and a controlling spring connected to the shank and sliding in the groove of the shifting member and acting to automatically shift the retaining element to open position when the locking member is released and further exerting a holding pressure on the locking member when the latter is in locking position.

In testimony whereof, I affix my signature hereto.

THEOPOLIS NOWLAND.
